Attorney

UNITED STATES PATENT OFFICE.

HARLEY BARKMAN, OF ROCHESTER, INDIANA.

CAMP BED.

Application filed June 5, 1922. Serial No. 565,929.

To all whom it may concern:

Be it known that I, HARLEY BARKMAN, a citizen of the United States, residing at Rochester, in the county of Fulton, State of Indiana, have invented a new and useful Camp Bed; and I do hereby declare the following to be a full, clear, and exact description of the invention, such as will enable others skilled in the art to which it appertains to make and use the same.

The invention relates to camp beds and has for its object to provide a foldable bed adapted to be attached to the running board of an automobile and so constructed that when folded it will be supported on the running board in a position where it may be easily and quickly unfolded for use. Also to provide one of the bed sections with a closed bottom, which when the bed is folded forms a closure for the outside of the bed and when the bed is partially unfolded forms a table top.

A further object is to provide a folded running board carried bed comprising a section hingedly connected to the running board, a second section having a link connection with the running board carried section and hinged members carried by one of said sections adapted to be disposed between the adjacent ends of the sections, for bracing the sections in relation to each other. Also to provide foldable legs and a foldable foot member for the bed.

A further object is to provide a canvas bottom for the bed, one end of which has spring connections with the running board carried section adjacent the running board and the other end has adjustable connections with the outer end of the outer section of the bed.

A further object is to provide a pivoted U-shaped frame pivoted to the running board, the transverse portion of said U-shaped frame cooperating with notches in the underside of the running board carried section and forming means for holding the bed in folded position.

With the above and other objects in view the invention resides in the combination and arrangement of parts as hereinafter set forth, shown in the drawings, described and claimed, it being understood that changes in the precise embodiment of the invention may be made within the scope of what is claimed

without departing from the spirit of the invention.

In the drawings:

Figure 1 is a top plan view of the bed showing the same unfolded.

Figure 2 is a side elevation of the bed showing the same unfolded.

Figure 3 is a front elevation of the bed.

Figure 4 is a front elevation of the bed showing the same in folded position.

Figure 5 is a top plan view of the bed and a portion of the running board showing the bed partially unfolded and in position to be used as a table.

Figure 6 is a side elevation of the bed showing the same folded and on the running board of an automobile.

Figure 7 is a side elevation of the bed showing the same partially unfolded.

Referring to the drawing the numeral 1 designates the running board of a conventional form of automobile and 2 brackets carried thereby. Hingedly connected at 3 to the brackets 2 is the inner section 4 of the bed. The bed section 4 is U-shaped and comprises the transverse rail 5 and the side rails 6. Hingedly connected at 7 to the side rails 6 are elongated members 8, which when moved into alignment with the side rails 6 engage the adjacent ends 9 of the side rails 10 of a second U-shaped frame 11 and hold the rails 6 and 10 in alignment. The rails 6 and 10 are hingedly connected at 12 to elongated members 13, which members engage the under side of the members 8 and assist in bracing the members and at the same time allow the section 11 to be folded upwardly and inwardly from its position shown in Figure 2 onto the frame 4 after the members 8 have previously been folded onto the rails 6. Pivotedly connected to the rails 6 at 14 are supporting legs 15, which legs when moved downwardly out of registration with the rails 6 engage the ground and support the frame 4 in a horizontal position. The frame 11 has pivotally connected at 16 to its 90 opposite sides supporting legs 17, said legs being limited in their movement by angle members 18 thereby preventing folding of the legs after they have been extended. The bed is preferably provided with a canvas bottom 19 so that the same may easily fold, said bottom at one of its ends is provided with a bar 20, to which coiled springs 21 are

90

95

100

105

connected, said coiled springs 21 having their other ends connected at 22 to the transverse rail 5, and form means for resiliently supporting the bottom 19. The other end of the bottom 19 is provided with a bar 23 through which adjusting screws 24 extend, said adjusting screws also extending through the bar 25 of the frame 11, and by means of which adjusting screws the canvas bottom 19 may be tensioned as desired. When the frames 11 and 4 are folded onto each other the canvas bottom 19 also folds as clearly shown in Figures 6 and 7 and is disposed between the frames 4 and 11 in such a manner that it will not interfere with the folding of the bed. The frames 4 and 11 are preferably braced by brace bars 26 which extend angularly across the corners of the frame and are preferably formed from metal thereby allowing the maximum bracing efficiency and at the same time reducing the bulk of the device as a whole.

The frame section 11 is provided with a U-shaped foot rest 27, the arms 28 of which are pivotally mounted at 29 on brackets 30 carried by the ends of the bar 25 and extending upwardly and overlying the upper side of the bar 25. Foot rest 27 when in extended position as shown in Figure 2 is held in a vertical position by braces 31, which braces are pivotally connected at 32 to the foot rest arms 28 and at 33 to side rails 10 of the frame 11 and are provided with a conventional form of break joint 34 which allow the foot rest 27 to be folded on the frame 11 in such a manner that during the folding of the bed to its folded position on the running board it will not interfere with the folding operation. The underside of the frame 11 is provided with a metallic sheet 35, which when the device is folded to the positions shown in Figures 5 and 7 forms a table top thereby allowing the foldable bed to be used as a camp table. Pivotally connected at 36 to the brackets 2 adjacent the rear side of the running board 1 are the arms 37 of a U-shaped frame 38. The transversely disposed portion 39 of the frame 38, when the device is folded to the position shown in Figure 6 is received in notches 40 in the under sides of the rails 6 of the frame 4 and is held in said notches by means of the pivoted members 41, therefore it will be seen that the bed when folded is held in folded position by the U-shaped frame 38 and held by said frame securely and rigidly on the running board 1. When it is desired to unfold the bed the U-shaped frame 38 is released and moved downwardly out of engagement with the notches 40, after which the device as a whole is moved outwardly on the hinging point 3 in the position shown in Figure 7 and the legs 15 are moved to vertical positions for supporting the device. The bed being unfolded to the

position shown in Figure 7, the operator grasps the frame 11 and unfolds the same outwardly until it is in substantially the same horizontal plane as the frame 4, at which time the hinged members 8 are folded 70 outwardly and disposed between the adjacent rails 6 and 10 of the frames 4 and 11. The bed frames having been extended, the folding legs 17 are moved to vertical position for supporting the bed at its outer end 75 after which the foot rest 27 which is folded on the upper side of the frame 11 is moved to a vertical position as shown in Figure 2.

The section 4 is provided with a transversely disposed head rest 42, said head rest 80 being provided with arms 43 which when moved to the dotted line position shown in Figure 7 engage the brackets 2 and support the head rest portion 44 at an incline. However when the device is folded the head 85 rest member 44 and the arms 43 are moved to the full line position shown in Figure 7, in which position they will not interfere with the folding inwardly onto the running board of the sections after having been 90 folded to the position shown in Figure 7.

From the above it will be seen that a folding camp bed is provided for automobile running boards which is simple in construction, and when extended the parts will be 95 rigidly held.

The invention having been set forth what is claimed as new and useful is:—

1. The combination with an automobile running board, of a foldable bed carried thereby, said bed comprising a frame hingedly connected to the running board, a second frame, link connections between the adjacent ends of said frames, rigid hinged members carried by one of the frames and 100 interposed between the adjacent ends of the frame when extended and above the link connections, said link connections forming means whereby the frames may be folded into registration, and moved to vertical 105 positions on the running board, a U-shaped frame pivoted to the running board spaced from the hinging point of the running board carried frame and means carried by the under side of the running board carried frame 110 for receiving the transverse portion of the U-shaped frame and preventing outward displacement of the bed when folded. 115

2. The combination with a foldable bed carried by the running board of an automobile, said bed comprising a plurality of foldable sections foldable upon each other and onto the upper side of the running board, of means for holding said bed in folded position on the running board, said 120 means comprising a U-shaped frame, the U-shaped frame having its arms pivotally connected to the running board adjacent its rear side, the transverse portion of the U-shaped frame being disposed outside of the folded 125 130

bed, and means carried on the outer side of the folded bed for receiving and holding said transverse portion of the U-shaped frame and the U-shaped frame holding the 5 folded bed in vertical position on the running board.

In testimony whereof I have signed my

name to this specification in the presence of two subscribing witnesses.

HARLEY BARKMAN.
